KEY ACTION AND KEY MECHANISM.

Application filed November 5, 1923. Serial No. 672,871.

My invention relates to key-action and key mechanism for typewriters of the conventional class and other type-bar and key-operating machines, the type-bar and key-lever being so connected with a trip link coupling, comprising two connected links, one being connected to the type-bar and the other to the key lever. This coupling moves the type-bar to the printing point upon the 5
de-
pression of a key-lever; means breaking re-
versely the said coupling after the printing
impact of the type-bar, for the return of the
type-bar to normal position while the key-
lever is held depressed. The type-bar ac-
tion, more in detail, also includes a vibra-
tory element controlling the operation of
said coupling and also type-bar returning
elements.

A still further object of my invention is
20 to provide means of the character specified
above with which in the main is in the
nature of a structure that may readily be in-
corporated in certain typewriting machines
with only slight modification of the struc-
25 tural features of said machines as they now
exist. I have shown my invention embod-
ied, in the present instance, in a typewriter
similar to the Underwood Standard machine,
and in which the invention may be readily
30 incorporated by slight modification of the
structural features of the machine in effect-
ing such incorporation. It should be un-
derstood, however, that the invention is not
restricted to use in a machine of this type,
35 but may be employed wherever found avail-
able.

The desired principle of operation, new
mechanical functions, operative expedients,
and other objects and advantages will here-
40 inafter be described in the following dis-
closure and will be more particularly point-
ed out in the appending claims. In the ac-
companying drawing wherein like reference
characters indicate corresponding parts in
45 the various views.

In the drawing Figure I, is a vertical sec-
tion of a typewriter, one key-action only
being shown in normal position; Fig. II,
50 represents a view of the key-mechanism
similar to Fig. I, the key-lever being shown
depressed and responding the type-bar.
Fig. III, also key-mechanism similar to Fig.
I, the key-lever being shown in a depressed
55 position and the type-bar returned to its ini-
tial position. Fig. IV is a skeleton view of

the key-mechanism for illustrative purposes
in describing the mode of operation of the
machine shown. It is understood, of course,
that for the sake of clearness and to avoid
complication of drawings the applicant has 60
omitted to show the remainder of the key-
levers and type-bars as well as other devices
necessary or advisable in the complete
machine.

In the embodiment in Fig. I, 1 indicates 65
the frame of a typewriter 1^a indicates the
front and 1^b the rear, having a common
power driving paper carriage 2 supported
in the rear on guide rod 3 and in front on
guide rod 4; 5 indicates the common platen 70
carried by the paper carriage 2; 6 indicates
one of the usual type-bars carrying the type
7 at its front end, and having the usual pin
and slot connection 8 and 8^a at the heel of
the rear end, and is arranged to turn on
pivot 9 in the form of a segment disposed
vertically below the frame face of the plate
10, thereby providing the type 7 with a com-
mon printing point A as the type-bar 6 turns
on pivot 9 from the normal horizontal posi-
tion of rest on the segment II in the usual
manner.

12 indicates one of the duangular key-
levers carrying at the front end finger-key
13, the rear end pivoted at 14 to bar 14^a 85
Fig. I, in the rear of the machine, and is kept
normally in its elevated position by the
usual spring 15 supported by bar 15^a at nor-
mal rest of key-lever, bearing against the
underside of stop-bar 15^b above the key-lever 90
12. The duangular key-lever 12 is formed
with double angle (duangular) 16 and 16^a
arranged to provide a forward under angle
seat 17 for a coupling pivot hereinafter de-
scribed, and also provides a rear upward 95
angle for pivot rod 19 and bar 20.

The key-lever 12 is described as having
two incidents of operation, namely: the inci-
dent of depression and the incident of re-
lease. The incident of depression is dis-
closed by the movement of duangular key-
lever 12 from radius B to radius C, and the
incident of release is disclosed by the move-
ment of the duangular key-lever 12 back
from radius C to radius B. The type-bar 105
6 is described as having two incidents of
operation, namely: incident of response and
the incident of recoil. The incident of re-
sponse of the type-bar 6 is disclosed by the
movement of the type-bar from its initial 110

rest radius E to the printing point A, radius F, forming arc G from pivot 9. The incident of recoil of type-bar 6 is disclosed by its movement from the printing point A back to normal rest E. These incidents of operation are, of course, common in type-bar actions so far as the incident of response, E to A, of the type-bar 6 occurs simultaneously with the incident of depression, B to C, of key-lever 12, and the incident of recoil, A to E of the type-bar occurs simultaneously with the incident of release, C to B, of the key-lever, but, the novelty of my invention relative to the correlation of incidents of operation of the duangular key-lever with that of the type-bar, is in providing the operative expedient by which both the incident of response, E to A, of the type-bar and the incident of recoil, A to E, occur during the one incident of depression, B to C, of the duangular key-lever. This operative expedient is accomplished in this case, by a trip link coupling being the principal subject matter of this application, connecting the key-lever with the type-bar, herein-after further described.

18 indicates one of a series of vertically disposed vibratory levers, corresponding in number with the type-bars 6 and duangular key-levers 12. Lower ends of the vertically disposed vibratory levers 18 are pivoted at 19 in a bar 20 extending across the machine above and within the rear and upward angle of said duangular key-lever.

22 an angularly formed draw link and 23 is a depending thrust link of said trip link coupling, which connects the type-bar with the duangular key-lever.

Intermediately of the ends of the angular formed draw link 22 is pivoted at 25 the end of vertically disposed lever 18, and the lower end of the angular formed draw link 22 crosses the key-lever 12 intermediately its ends and is pivoted at 24 to the lower end of the depending thrust link 23, the upper end of the depending thrust link 23 being pivoted at 26 to the duangular key-lever 12 intermediately of angles 16 and 16^a and on opposite side of key-lever to that of the angular formed draw link 22.

55 The pivotal manner of coupling the type-bar and key-lever discloses a trip link coupling having all links connected as a contradistinction between devices comprising a detachable connection or gap at some point between the key-lever and the type-bar after said type-bar has been given the movement necessary to effect the printing and before the key-lever has completed its movement.

60 The relative normal position of pivots 24, 25 and 26 engaged in a line approximately perpendicular to the key-lever 12, discloses the trip link coupling to be perpendicularly disposed as distinguished from being engaged horizontal to the key-lever.

It will be observed that links 22 and 23 constituting the trip link coupling operate in a plane crossing the key-lever. Also link 22 operates in front of pivot 19 and cross bar 20 which discloses said trip link coupling to be frontly disposed.

27 is a returning spring front end engaging one of the plurality of holes 27^a in the rear edge of the angular formed draw link 22 and the rear end engaging hole 27^b in the upper edge of the duangular key-lever 12 near its rear end. The threefold function of the return spring 27 is effected by both of its ends, engaging working parts moving in opposition to the tension of said spring, namely: it returns the vibratory lever 18 normally in position shown in Fig. I, thereby returning the type-bar 6 to normal position E after operation; and finally it returns the key-lever 12 to normal position of rest when the common spring 15 shall have been eliminated. Hence the energy stored by depressing the duangular key-lever 12 and responding the type-bar 6 in opposition to the tension of the return spring 27 returns both the type-bar and key-lever to normal position, constituting the novel function of said element 27.

28 is an extended trip toe of the angular formed draw link 22, and is designated as a fulcrum trip toe, pivot 24 being the fulcrum point about which the angular draw link 22 turns in cooperating with trip-rod 30 in moving the lower end of the depending thrust link forwardly out of seat 17. The trip-rod 30 is composed of a round metal core 30^a extending across the machine on which are strung a series of frictionless rollers or bands bead-like fashion, corresponding to the number of keys in the machine, each band communicating with each fulcrum trip toe. Draw link 22 cooperates with return rod 29, Fig. III in restoring the coupling to normal position during the incident of release of the duangular key-lever 12.

115 The new mechanical structure, movements and operation thereof are the important factors of the invention in providing the desired function of the key-action. A further description of the operative principle, therefore, follows: The geometric circle H H, Fig. IV, with a vertically inclined diametrical line J J from the pivots 24 to 25 circumscribes what is termed the actuating plane. Pivot 24 is designated as the lower border pivot of the actuating plane and pivot 25 is designated as the upper border pivot. The vertically inclined diametrical line J J of the actuating plane, from the lower border pivot 24 to the upper border pivot 25, indicates the divert tension line and divides the actuating plane into the forward zone of response K and the rear zone of reaction L; the forward zone of response K having 120 125 130

to do with the response of the type-bar 6 from radius E to radius F while the duangular key-lever 12 is being depressed from radius B to radius D; and the rear zone of 5 reaction L having to do with the recoil of the type-bar 6 from the printing point A to radius E at rest while the duangular key lever 12 is being continually depressed from radius D to radius C of depression. 10 The normal or idle position of the depending thrust link 23 operates in the forward zone of response K as shown in Figs. I, II and IV. It is necessary that the angular formed draw link 22 be also of such length between 15 pivots 24 and 25 and be in such form and so engaged in such fashion as to permit the interior pivot 26 to oscillate between the lower border pivot 24 and the upper border pivot 25 in crossing and recrossing the divert tension line J J. The angular formed draw link 22, therefore, is the major in length of the trip link coupling, and the depending thrust link 23 is the minor. In this case, the elements 20 22 and 23 of the trip link coupling are folded 25 during the incident of depression from radius B to radius D of the duangular key-lever 12 and simultaneously with the incident of response of type-bar 6 from radius E to printing point A; and the link fold 30 elements 22 and 23 unfold during the remainder of depression, radius D to radius C of the duangular key-lever 12 simultaneously with the recoil of type-bar 6 from printing point A back to radius E. 35 The angle stop seat 17 provided by the duangular key-lever 12 stops the lower border pivot 24 and effects responsive or operative tension-lock of the depending thrust link 23 under influence of returning spring 40 27 as the duangular key-lever 12 is being depressed from radius B to radius D. This operative tension-lock of the depending thrust link 23 is also described as contractive tension-lock or thrust meaning that while the 45 duangular key-lever 12 is being depressed, the energy required to respond the type-bar 6 effects contractive pressure or thrust from interior pivot 26 to lower border pivot 24 instead of expansive tension or pull. The contractive tension of the depending thrust link 50 23 stops its oscillation and is moved endwise downward with the duangular key-lever 12, as shown in Fig. II, as the vertically disposed vibratory lever 18 throws the upper border pivot 25 forward until the interior pivot 26 crosses the divert tension line J J into the rear zone of reaction L. Simultaneously with contractive tension-lock of 55 depending thrust link 23, the angular formed draw link 22 operates under expansive tension between the lower border pivot 24 and the upper border pivot 25 while the duangular key-lever 12 is being depressed from radius B to radius D to respond the type-bar 6 from radius E to printing point A, and

the expansive tension of the angular formed draw link 22 being relaxed while the duangular key-lever 12 continues the incident of depression from radius D to radius C and simultaneously with the recoil of the type-bar 6 from the printing point A back to radius of rest E. 70

The dotted line M M indicates the correlative relationship of the above named pivots during the process of operation viz: Dotted line M M, Fig. I shows where the tri-pivotal relationship forms obtuse angle at the interior pivot 26 pointing forward within the forward zone of response during normal position and effecting response of the type-bar during depression of key-lever. Dotted line M M, Fig. II shows the alignment of the tri-pivotal relationship at the time the type-bar completes its response or impact and begins to recoil. Dotted line M M, Fig. III 80 shows the obtuse angle at interior pivot 26 formed by the tri-pivotal relationship pointed backwards within the zone of reaction as the type-bar recoils. 85

Inherent to the common key-action certain key-levers accidentally and slightly depressed part way down suspend their respective type-bars along the type-arc G interfering or "piling" with the response and recoil of intentionally struck keys; but the present invention provides the exigency that when the finger key 13 is slowly depressed, the type 7 responds to the degree on arc G corresponding to the radius of depression of the duangular key-lever 12 and from there they 90 automatically recoil without having impact with the platen. This is an inherent exigency of my invention referred to as the operative expedient by which type-bars responding to slowly depressed keys part way down automatically recoiled without interfering with responding type. This operative expedient is accomplished by plate 31 designated as recoil timer plate, having slot 32 and slot pivot 33 fastened tightly therein and turning in hole in the duangular key-lever 12 and set screw 34 fastened to the side of the duangular key-lever 12, having a head larger than slot 32 but body of screw 34 being much smaller than slot 32 permitting plate 31 to 100 105 slightly drop lower than the lower edge of said duangular key lever and slightly oscillate on pivot 33 when it strikes the top of trip-rod 30. The type-bar having no momentum when the duangular key-lever is being slowly depressed, recoil timer plate 31 pushes the depending thrust-link 23 forward out of tension lock about the time the type 7 raises two-thirds of arc G and without impacting printing point A it drops back to E. 110 115 120 125

What I claim as new and desire to secure by Letters Patent is:

1. In a typewriting machine, a type bar, a key lever, actuating means at all times operatively connecting the type bar and key 130

lever to move the type bar to the printing point upon depression of the key lever, means actuating said connection to return the type bar after the printing impact while the key lever is in depressed position.

2. In a typewriting machine, a type bar, a key lever, a reversely breaking actuating connection operatively connecting the key lever and type bar for moving the type bar to the printing point upon depression of the key lever, means reversely breaking said connection after the printing impact to return the type bar to normal position while the key lever is in depressed position.

15 3. In a typewriting machine, a type bar, a key lever, actuating means at all times operatively connecting the type bar and key lever comprising a trip link coupling for moving the type bar to the printing point upon depression of the key lever, means reversely breaking said coupling after the printing impact of said type bar for return of the type bar to normal position while the key lever is in depressed position.

25 4. In a typewriting machine, a type bar, a key lever, a reversely breaking actuating connection at all times operatively connecting the key lever and type bar comprising a trip link coupling to move the type bar to printing point upon depression of the key lever, means reversely breaking said coupling after the printing impact for returning the type bar to normal position while the key lever is in depressed position.

35 5. In a typewriting machine, a key lever comprising an upward and lower angles intermediately of its ends, a type bar, a trip link coupling at all times operatively connecting said key lever and type bar comprising an angular formed draw link and a depending thrust link for moving said type bar to printing point upon depression of the key lever, a vertically disposed vibratory lever, a pivotal rod for lower end of said vertically disposed vibratory lever, a pivot connecting the upper end of said vertically disposed vibratory lever to the angular formed draw link intermediately of its ends, means reversely breaking said coupling after

40 the printing impact of the type bar, means for the return of the type bar to normal position while key lever is in depressed position, means for restoring said coupling to normal operative position upon release of the key lever.

50 6. In a type key action, a key lever comprising an upward angle and a lower angle, a type bar, a trip link coupling at all times operatively connecting the key lever and type bar comprising an angular formed draw link, a depending thrust link pivoted intermediately of the ends of said key lever and connecting said draw link moving the type bar to printing point upon depression of key lever, a vertically disposed vibratory

lever moving said coupling forwardly, means reversely breaking after the printing impact of the type bar to return the type bar to normal position while the key lever is in depressed position, means restoring said coupling to normal operative position upon release of the key lever.

7. In combination, a key lever comprising an upward angle in the rear and a lower angle forwardly thereof, a type bar, a segmental pivot rod therefore, a trip link coupling comprising an angular formed draw link pivoted to the type bar, a depending thrust link pivoted to the draw link and to the key lever moving the type bar to printing point upon depression of key lever, a vertically disposed vibratory lever pivoted at its lower end within the upper angle of said key lever, a pivot connecting the upper end of said vertically disposed vibratory lever to the side of said angular draw link diverting the movement of the latter forwardly, means reversely breaking said coupling after printing impact of the type bar, means restoring the type bar to normal position while key lever is in depressed position, means restoring said coupling to normal operative position upon release of said key lever.

8. In a typewriter or like machine, a key lever comprising a key, a fulcrum rod on which the key lever is pivoted, a trip link coupling comprising an angular formed draw link connected to a vertically disposed vibratory lever and a depending thrust link depending from said key lever intermediately of the angles thereof and connected to said draw link, a type bar with operative pin and slot connection with the angular formed draw link moving to printing point upon depression of key lever, a vertically disposed vibratory lever connected to an angular formed draw link, means reversely breaking said coupling after the printing impact of the type bar, means returning the type bar to normal position while the key lever is in depressed position, means restoring said coupling to normal operative position upon release of the key lever.

9. In a type key action for a typewriting machine, a type bar, a pivot therefore, an angular formed draw link connected to the type bar, a key lever with two angles intermediately of its ends, a depending thrust link pivotally depending intermediately the angles of said key lever, a pivot beneath said key lever connecting said draw link and thrust link moving the type bar to printing point upon depression of the key lever, a vibratory lever extending upwardly from its pivot and connecting said draw link intermediately of the ends of the latter actuating same forwardly, means reversely breaking said coupling after the printing impact of the type bar for returning the type bar to

- normal position while key lever is in depressed position, means restoring said coupling to normal operative position upon release of the key lever.
- 5 10. In a key action for key operating machines, a type bar, an angular formed draw link connected to said type bar, a depending thrust link connected to said angular formed draw link, a key lever, an under stop rest for lower end connection of said angular draw link and depending thrust link, said elements moving the type bar to printing point upon depression of key lever, a vertically disposed vibratory lever actuated for wardly by a draw link, means reversely breaking said coupling after the printing impact of the type bar, means returning the type bar to normal position while key lever is in depressed position, means restoring said coupling to normal operative position upon release of the key lever.
- 10 15 20 25 30 35 40 45 50 55 60 65 70 75 80 85 90 95 100 105 110 115 120 125 130
11. In a type key mechanism, a key lever having two angles intermediately of its ends, a depending thrust link pivoted at the side of the key lever intermediately of the angles of the latter, a type bar, an angular formed draw link pivoted to said type bar and extending downwardly crossing said key lever and pivoted to the depending thrust link moving the type bar to printing point upon depression of the key lever, a vertically disposed vibratory lever pivotally operated by the angular formed draw link vibrating the latter forwardly reversely breaking said coupling after the printing impact of the type bar, means returning the type bar to normal position while key lever is in depressed position, means restoring said coupling to normal operative position upon release of the key lever.
12. In a type key mechanism, a type bar, a key lever having an upper rear-angle and a lower forward angle, a trip link coupling comprising an angular formed draw link and a depending thrust link engaged on the opposite sides of the key lever, a pivot connecting said angular formed draw link and depending thrust link beneath said key lever oscillating within said lower-forward angle thereof moving the type bar to printing point upon depression of the key lever, a vertically disposed vibratory lever having pivotal connections with the angular draw link vibrating the upper end of the latter forwardly, means breaking reversely said coupling after the printing impact of the type bar, means returning the type bar to normal position while the key lever is in depressed position, means restoring said coupling to normal operative position upon release of the key lever.
13. In a key action mechanism, a key lever, a depending thrust link extending downward from said key lever, an angular formed draw link disposed substantially perpendicu-
- lar to said key lever crossing the latter intermediately of its ends and pivoted to said depending thrust link, a type bar with a pin and slot connection with the upper end of said angular formed draw link moving to printing point upon depression of the key lever, a vertically disposed vibratory lever, upper end thereof pivoted intermediately the ends of said angular formed draw link, a pivot rod for said vertically disposed vibratory lever engaged within an upward-rear angle of said key lever, means breaking reversely said mechanism after the printing impact of the type bar, means returning the type bar to normal position while the key lever is in depressed position, means restoring said coupling to normal operative position upon release of the key lever.
14. In a typewriting machine, an angular formed draw link with forwardly disposed vertex, a vertically disposed vibratory lever connected to said angular formed draw link, a key lever comprising a rear upward angular space for the lower end of said vertically disposed vibratory lever, a depending thrust link pivotally depending from said key lever, a pivot connecting the lower end of said angular formed draw link to the lower end of said depending thrust link operating within a lower forward angle of said key lever, a type bar directly operated by said angular formed draw link moving to printing point upon depression of the key lever, means breaking reversely said coupling after the printing impact of the type bar, means returning the type bar to normal position while key lever is in depressed position, means restoring said coupling to normal operative position upon release of said key lever.
15. In a typewriting machine, a trip link coupling comprising a relatively long angular formed draw link and a relative short depending thrust link pivoted thereto, a type bar pivoted to the upper end of said angular formed draw link, a vertically disposed vibratory lever pivoted intermediately of the ends of said angular formed draw link, a key lever pivoted to said depending thrust link for responding the type bar to printing point upon depression of the key lever, means reversely breaking said coupling after the printing impact of the type bar, means recoiling the type bar while the key lever is in depressed position, means restoring said coupling to normal operative position upon release of the key lever.
16. In a typewriting machine, a type bar, a key lever, an angular formed draw link, a depending thrust link pivoted thereto, a vertically disposed vibratory lever actuating said angular formed draw link forwardly moving the type bar to printing point upon depression of the key lever, a fulcrum trip toe comprising the lower end of

said angular formed draw link, a trip rod communicating with said fulcrum trip toe reversely breaking said coupling after printing impact of the type bar, means restoring 5 the type bar to normal position while key lever is in depressed position, means restoring said coupling to normal operative position upon release of the key lever.

17. In a recoil mechanism for a type key, 10 a type bar, a key lever, a depending thrust link pivotally depending from the side of said key lever, a draw link moving said type bar to printing point upon depression of key lever a vertically disposed vibratory lever 15 controlling the movement of said angular formed draw link, a fulcrum trip toe comprising the lower end of said angular formed draw link cooperating with trip rod breaking reversely said coupling after the printing 20 impact of the type bar, means returning the type bar to normal position while key lever is in depressed position, means restoring said coupling to normal operative position upon release of the key lever.

18. In a key action for a typewriting machine, a type bar, a key lever, a depending thrust link pivoted to said key lever, an angular formed draw link pivoted to said thrust link, a vertically disposed vibratory 30 lever controlling the action of said angular formed draw link for responding the type bar to printing point upon depression of the key lever, a fulcrum trip toe provided by said draw link, a trip rod communicating 35 with said fulcrum trip toe breaking reversely said coupling after the printing impact of the type bar, a return spring connecting said key lever and angular formed draw link returning the type bar to normal position 40 while said key lever is held depressed and elevating said key lever to normal position upon its release, means restoring said coupling to normal operative position upon release of the key lever.

19. In a mechanical movement for a typewriter key, a type bar, a key lever, a trip link coupling comprising a thrust link and a draw link at all times operatively connecting the key lever and type bar, a vibratory 50 lever controlling the movement of said coupling, a border pivot connecting said draw link to said vibratory lever at the border of an operative plane, another border pivot connecting said depending thrust link and draw link at another border point of said operative plane, an interior pivot connecting said depending thrust link to said key lever interior of said operative plane and within 55 a zone of response during normal position of said coupling responding said type bar to printing point upon depression of said key lever, an alignment of said border pivots

and interior pivot upon printing impact of said type bar, changing reversely said pivotal relationship within a zone of reaction 65 returning said type bar to normal position while key lever is in depressed position, means restoring said coupling to normal operative position upon release of the key lever.

20. In a mechanical movement for a typewriter key, a type bar, a key lever, a trip link coupling comprising a depending thrust link and an angular formed draw link connecting the key lever and type bar, a vertically disposed vibratory lever controlling 70 the movement of said coupling, an upper border pivot connecting said draw link to said vibratory lever at the upper border of an operative plane, a lower border pivot connecting said depending thrust link to said draw link at the lower border of said operative plane, an interior pivot connecting said depending thrust link to said key lever interior of said operative plane and within 75 a forward zone of response during normal position of said coupling responding said type bar to printing point upon depression of said key lever, a vertical alignment of said border pivots and interior pivot upon printing impact of said type bar, changing 80 reversely said pivotal relationship within a backward zone of reaction returning said type bar to normal position while key lever is in depressed position, a return bar above 85 said key lever communicating with front edge of said angular draw link returning said coupling to normal operative position upon release of the key lever.

21. In a key action for a typewriting machine, a type bar, a key lever, a trip link coupling comprising an angular formed draw link and a depending thrust link, a return spring supported by the angular formed draw link and key lever moving in opposition to the tension thereof, a recoil timer plate operatively pivoted at the side of said key lever, front end communicating with said depending thrust link and lower edge extending slightly lower than the key lever, a trip rod extending laterally beneath said key lever communicating with the lower edge of said recoil timer plate reversely breaking said coupling returning the type bar to normal position without printing impact upon the slowly depression of the key lever, a return bar above the key lever communicating with the angular formed draw link returning said coupling to normal position upon release of the key lever.

Signed at Fort Collins, in the county of Larimer and State of Colorado, this 1st day of December A. D. 1926.

ORVILLE U. DESHA.
